UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,275,387.

Specification of Letters Patent. Patented Aug. 13, 1918.

Application filed May 6, 1914. Serial No. 836,710.

To all whom it may concern:

Be it known that I, JOHN E. CHALMAN, a citizen of the United States, residing at Chicago, in the county of Cook, State of Illinois, have invented certain new and useful Improvements in Presser-Feet for Sewing-Machines, of which the following is a description, reference being had to the accompanying drawing and to the figures of reference marked thereon.

The invention relates to new and useful improvements in a presser foot for sewing machines, and more particularly to a presser foot which is so constructed that connecting 15 rows of stitches may be made between articles and the enchain loops properly held and fed from the machine.

The object of the invention is to provide a presser foot of the above character with 20 an auxiliary portion which engages the enchain loops and presses the same against the work support when there is no material in the machine, so as to prevent the looper from drawing the loops back into the needle 25 throat and thus prevent chaining-off.

A further object of the invention is to provide a presser foot of the above character with an auxiliary portion which is so constructed and arranged that when a piece of 30 material to be stitched is fed underneath the presser foot and the main foot raised or tilted thereby, the auxiliary foot still cooperates with the work support and feed dog in holding and feeding the chain of loops 35 which connect the previously stitched material to the material passing underneath the foot.

These and other objects will in part be obvious, and will in part be hereinafter more 40 fully disclosed.

In the drawings which show by way of illustration one embodiment of the invention—

Figure 1 is a vertical sectional view 45 through a presser foot embodying my improvements and showing the auxiliary feed dog holding the enchain loops as an article which has been stitched is passing from underneath the foot;

Fig. 2 is a similar view, showing the main portion of the presser foot and the auxiliary portion of the presser foot engaging the material which is being fed underneath said foot;

Fig. 3 is an enlarged detail, showing the

auxiliary foot and the manner of clamping and holding the loops during chaining-off;

Fig. 4 is a view similar to Fig. 1, showing the main presser foot tilted when the material is first fed underneath the foot and 60 the auxiliary feed dog holding the chain of stitches until the needle engages the material;

Fig. 5 is a plan view of the presser foot; and

Fig. 6 is a sectional view on the line 6—6 of Fig. 5.

My improved presser foot consists of a supporting shank 1, which is adapted to be clamped to the presser bar 2 in the usual manner. The main foot portion 3 is pivotally secured thereto by a bolt 4. Said main foot portion is provided with an upwardly inclined forwardly projecting toe 5 and an upwardly inclined rearwardly projecting heel 6. Said main foot portion, centrally thereof, both longitudinally and transversely, is formed with a slot 7, in which is located an auxiliary foot 8. A bar 9 bridges the slot 7 at the rear end thereof and is secured to 80 the main portion thereof. The auxiliary foot 8 is pivoted to a stem 10, which extends through an opening in the bar 9. A spring 11 fixed to the main portion of the presser foot bears on the upper end of this stem 10 85 and normally forces the auxiliary foot downward. A pin 12 extends through the stem and is adapted to engage the upper face of the bar 9 to limit the downward movement of the foot. 90

This auxiliary foot is cut-away slightly at the rear end thereof, as at 13. The front portion of the foot is turned up, as at 14, and said auxiliary foot has a needle throat 15 extending therethrough. The stem 10 95 extends into a recess 16 in the upper side of the auxiliary foot and a pivot screw 17 passing through the stem pivots the foot to the stem. This recess is so formed that the auxiliary foot may oscillate on said stem. 100 The extreme end 18 of the toe of the auxiliary foot is adapted to engage the main presser foot when the auxiliary foot is depressed to the limit of its downward movement, as clearly shown in Fig. 1. 105

The work support is formed with a slot 19, through which extends a feed dog 20, which is adapted to coöperate with this auxiliary foot. The main feed dog engages the material at each side of the auxiliary 110

foot, as indicated in dotted lines at 21, in Fig. 5. Said main foot may also engage the material directly in rear of the auxiliary foot. Said work support directly in rear 5 of the feed slot 19 is formed with a solid portion 22 which coöperates with the auxiliary presser foot.

One purpose of the auxiliary presser foot is to press the enchain loops of thread on 10 to the work support and feed dog 20, while an article is being fed out of the machine, as shown, for example, in Fig. 1, when the fabric being stitched passes beyond the needle. If there were no auxiliary feed 15 foot, the enchain loops would not be clamped against the work support, as the enchain loops are of less thickness than the material being stitched and the main foot is held raised from the work support 20 by the material which is still under the rear part of the foot. With my improved auxiliary presser foot, at this time said auxiliary presser foot is forced downward by the spring 11 and said foot engages the enchain loops and presses the same against 25 the work support and the foot also coöperates with the feed dog 20 in feeding these enchain loops. The clamping of the enchain loops, as shown in Fig. 3, prevents 30 the looper when moved laterally to avoid the needle from drawing the previously enchain loops through the slot in the work support, which would prevent the feeding of the loops. The auxiliary presser foot, 35 therefore, serves as a means for holding and feeding the enchain loops as the material leaves the machine. This auxiliary foot is yielding and, therefore, when the material being stitched is engaged by the needle, said 40 auxiliary portion of the foot will be raised into the slot in the main foot and will operate as a part of the main presser foot.

Another purpose of the auxiliary foot is to feed the enchain loops when an article 45 to be stitched is inserted underneath the presser foot. As the article is fed under the presser foot, as shown in Fig. 4, the main presser foot is tilted. The auxiliary foot will at this time also be tilted and the 50 heel of the auxiliary foot will engage the enchain loops and hold the same on the work support during the interlocking of the loops of the needle and looper until the material has reached the point where it is 55 engaged by the needle.

It is obvious that minor changes in the detail of construction and arrangement of parts may be made without departing from the spirit of the invention, as set forth in 60 the appended claims.

Having thus described my invention, what I claim as new and desire to secure by Letters Patent, is:

1. A presser foot for sewing machines, including in combination, a main foot, having

a slot formed therethrough, centrally thereof, an auxiliary foot located in said slot, a stem slidably mounted on said main foot to which said auxiliary foot is pivotally attached, means for yieldingly depressing said auxiliary foot, whereby the same may be moved a limited distance beneath the work engaging surface of the main foot, and means for limiting the downward movement of the auxiliary foot, said auxiliary foot having a needle opening therethrough. 70 75

2. A presser foot for sewing machines, including in combination, a main foot, a shank to which the main foot is pivotally attached, said main foot having a slot formed therethrough centrally thereof, an auxiliary foot located in said slot, a stem slidably mounted on said main foot to which said auxiliary foot is pivotally attached, a spring for yieldingly forcing said auxiliary foot downward, 80 a stop for limiting the downward movement of the auxiliary foot, said auxiliary foot having a needle opening therethrough and its work engaging face terminating in rear of said needle opening. 85

3. A presser foot for sewing machines, including in combination, a main foot, a shank to which the main foot is pivotally attached, said main foot having a slot formed therethrough centrally thereof, an auxiliary foot located in said slot, a stem slidably mounted on said main foot to which said auxiliary foot is pivotally attached, a spring for yieldingly forcing said auxiliary foot downward, a stop for limiting the downward movement of the auxiliary foot, said auxiliary foot having a needle opening therethrough and its work engaging face terminating in rear of said needle opening, the front portion of said 90 main foot and said auxiliary foot being inclined upwardly to facilitate the passing of the material underneath the same. 95

4. The combination with a work support having a needle opening therethrough and a solid portion in rear of the needle opening, a feed dog having a section thereof located in rear of the needle and said solid portion of the work support, a main presser foot, means for supporting said main presser foot, said main presser foot having a slot therethrough centrally thereof and extending from a point in rear of the solid portion of the work support to a point in front of the needle, an auxiliary presser foot located in the slot in the main presser foot and bodily movable below the work engaging surface of the main presser foot, said main presser foot being connected to its supporting means, whereby the same may 100 tilt upward at the forward end thereof when the material passes underneath said foot. 105 110 115

5. The combination with a work support having a needle opening therethrough and a solid portion in rear of the needle opening, 120 125 130

- a feed dog having a section thereof located in rear of the needle and said solid portion of the work support, a main presser foot, means for supporting said main presser foot, 5 said main presser foot having a slot therethrough centrally thereof and extending from a point in rear of the solid portion of the work support to a point in front of the needle, an auxiliary presser foot located in the slot in the main presser foot below the work engaging surface of the main presser foot, said main presser foot being connected 10 to its supporting means, whereby the same may tilt upward at the forward end thereof 15 when the material passes underneath said foot, said auxiliary presser foot being pivoted to its supporting means so as to be capable of tilting when the material passes underneath the same, and having a needle opening therethrough. 20
6. The combination with a work support having a needle opening therethrough and a solid portion in rear of the needle opening, a feed dog having a section thereof located 25 in rear of the needle and said solid portion of the work support, a main presser foot,
- means for supporting said main presser foot, said main presser foot having a slot therethrough centrally thereof and extending from a point in rear of the solid portion 30 of the work support to a point in front of the needle, an auxiliary presser foot located in the slot in the main presser foot below the work engaging surface of the main presser foot, said main presser foot being connected 35 to its supporting means, whereby the same may tilt upward at the forward end thereof when the material passes underneath said foot, said auxiliary presser foot being pivoted to its supporting means so as to be capable of tilting when the material passes underneath the same, and having a needle 40 opening therethrough, both the main presser foot and the auxiliary presser foot being inclined upwardly from a point adjacent the 45 needle.

In testimony whereof, I affix my signature in the presence of two witnesses.

JOHN E. CHALMAN.
